MEASURING DEVICE FOR OIL WELLS

Filed May 26, 1923

FIG. 1

FIG. 2

FIG. 4

FIG. 3

Inventor
Cooper L. Redfield.

UNITED STATES PATENT OFFICE.

CASPER L. REDFIELD, OF CHICAGO, ILLINOIS.

MEASURING DEVICE FOR OIL WELLS.

Application filed May 26, 1923. Serial No. 641,564.

My invention relates to measuring devices for oil wells, and has for its object the provision of means for determining the relationship between the oil in the well and a heater 5 inserted in the well for the purpose of heating the oil so as to melt any paraffin which may have solidified in a way to check the flow of oil to the well from the oil bearing sand or rock in which the well is.

10 To understand the requirements to be met by the present device it is to be noted that an oil well is a hole in the ground about six inches in diameter and some two thousand feet, more or less, in depth. The depth of the oil in the 15 well may be anything, but will here be assumed to be less than one hundred feet and liable at any time to subside to a depth of less than ten feet. In wells located near other wells, and operated under "vacuum", such 20 subsidence may occur at any time without warning.

The heaters used for heating such wells are usually electric heaters which may be of any type. The heater shown in the application of 25 George S. Hollister, Serial Number 574,649, filed July 13, 1922, or that shown in my application, Serial Number 587,616, filed September 11, 1922, are convenient ones to which the present invention may be applied. These 30 heaters are cylinders about four and one-half inches in diameter and from ten to twenty feet long. A wire cable is used to lower such a heater into the well to a position near the bottom, and an electric current is turned on. 35 As long as the heater is completely submerged in the oil in the well, the circulation of the oil will convey heat away, and the heater will not suffer. But if the oil should suddenly subside so as to uncover any considerable 40 part of the upper end of the heater, then the heater would become injured or destroyed by overheating unless the current was promptly shut off. One object of the present device is to give prompt warning at the surface of 45 the ground of any such subsidence at the bottom of the well.

Oil wells have tubular casings from the surface of the ground down to the oil bearing sand or rock, but in this oil bearing part 50 there is no casing. The result is that the walls of the oil bearing part of the well frequently cave in and fill up several feet of the lower end. This is particularly liable to occur

during heating. If a heater should be lowered to within a few feet of the bottom of 55 the well, and the wall should cave in so as to cover several feet of the lower end of the heater, then the buried part would become overheated and injured or destroyed. Another object of the present device is to give 60 warning of such partial burying of the heater so that overheating may be avoided.

In the accompanying drawings—

Fig. 1 is a side elevation of the apparatus at 65 the mouth of the well together with a section of the well with the heater in it, but near the top. In this view the length of the heater is much reduced as compared to its diameter.

Fig. 2 is a front elevation of the apparatus shown in Fig. 1;

Fig. 3 is an enlarged view of part of the apparatus as it appears in Fig. 1; and

Fig. 4 is a section on line 4—4 of Fig. 1.

Located adjacent to the mouth of the well 75 10 is a frame 11 in which is a slide 12 supported on springs 13. Carried in the slide 12 is a loose sheave 14 over which runs the cable 15 for lowering the heater 16 into the well 10. From the sheave 14 the cable passes to an idle sheave 17, and from here it extends to an ordinary hoisting apparatus for raising and lowering the heater in the well. That part of the cable between sheaves 14 and 17 is intended to be parallel with that part which extends down into the well. Beyond the sheave 17, the cable may extend in any direction.

In a part of the frame 11, which serves as a guide for the slide 12, is a recess 18 in which is a gear 19 provided with a spindle 20 having a bearing in frame 11, and secured to the slide 90 12 is a rack 21 arranged to engage gear 19. Adjacent to the gear 19 is a light clock spring 22 having one end secured to the frame at pin 23 and having the other end secured to the spindle. It will be evident that a movement 95 of the slide in its guide will turn the gear 19, and that the spring 22 will act to take up all slack between gear and rack in one direction. The spring is given an initial tension for that purpose.

Secured to the frame 11 by screws 24 is a dial 25, thru the hub of which runs the spindle 20. Adjustably secured to the spindle 20 by a nut 26 is a pointer 27 arranged to sweep over the graduations on the dial 25 when the 105 spindle 20 is rotated by reason of the slide 12

moving up or down in the frame 11. Secured to the flange of the dial 25 by a screw 28 (Fig. 4) is a piece of insulation 29, and on this is a metal piece 30 having fingers which lie in the path of the pointer 27. These parts are so constructed that the pointer 27 may pass over the fingers on piece 30, but will make electrical connection therewith when so passing. Connected to the piece 30 and to the frame 11, which latter is in electrical connection with the pointer 27 thru the spindle 20, is an electrical circuit 31 including a bell 32 and a battery 33. It will be evident that any movement of the slide 12 which will cause the pointer 27 to engage either finger of piece 30 will cause the bell 32 to sound an alarm.

On the upper end of heater 16 is an extension 34, and on the lower end is an extension 35. The parts 34 and 35 are of the same diameter as the heater 16, and are three or four feet long, more or less as may be desired. Their function is to act as displacement bodies in the oil of the well at the ends of the heater 16. The lower extension has an additional function which will be described later.

Electric heaters are pretty heavy. A heater ten feet long weighs about 750 pounds, and one twenty feet long weighs about 1,200 pounds. This makes the ordinary weight of heaters range from sixty to seventy-five pounds per foot in length. The cable used varies from one and one-half to two pounds per foot, with an average of about 1.7 pounds per lineal foot. The heavier cables are used for the longer heaters, and for the greater depths of well.

When the heater is suspended in the well near the surface of the ground, the downward pull on the sheave 14 is the weight of the heater plus a short length of cable, and this amount is multiplied by two because the pull is vertically downward on both sides of sheave 14. For convenience, however, we may consider the downward pull on sheave 14 to be the weight of the heater plus the weight of whatever part of the cable is within the well. In this proceeding, the extensions 34 and 35 will be considered as parts of the heater.

As the heater is lowered into the well, the downward pull on sheave 14, and consequently on slide 12 and springs 13, is increased by the increasing weight of cable in the well. The slide 12 is made an easy fit in the frame 11 so that any variation in downward pull will result in compression or expansion of springs 13, and consequently in a movement of the slide in the frame. As the gear 19 is pivoted in the frame and the rack 21 is secured to the slide, any movement of the slide is registered or indicated by a corresponding movement of the pointer 27 over dial 25.

For the sake of using concrete figures for illustrating purposes, it will be assumed that the heater, including its extensions, weighs

an average of sixty pounds per foot in length, and that the cable weighs two pounds per foot. It will also be assumed that the heater is of such diameter, or cross sectional area, that when it is immersed in the oil it will displace six pounds of oil for each lineal foot of such immersion. As a matter of fact, the heater may be of any weight per foot, the important things being the varying weight of cable and weight of displaced oil when the heater is immersed.

As the heater descends in the well, the springs 13 will become more and more compressed and the pointer or hand 27 will move over the graduations on the dial. As illustrated in the drawings, this movement will be in a clockwise direction. The graduations do not need to be at any particular scale as their principal object is to indicate movement rather than register weight. The relationship of the springs to the pointer movement may be such that the increasing weight of cable as the heater descends will cause the pointer to make several revolutions over the face of the dial. The object of such arrangement would be to have small variations of weight make a clearly perceptible movement of the pointer.

As the heater descends in the empty part of the well the pointer moves forward, but the instant the lower end of extension 35 enters the oil, this forward movement is suddenly changed to a backward movement which is twice as rapid as the forward movement was. This will be evident from the fact that for each foot of cable paid out there is an additional pull of two pounds on the cable at the sheave 14, but as soon as the heater enters the oil there is a buoyancy of six pounds per foot of immersion, and that the difference reduces the pull on sheave 14 by four pounds for each foot which the heater enters the oil. If the total length of heater and extensions is thirty feet, then the total immersion of the heater will result in a reduction of one hundred and twenty pounds on the cable, or twice that on the springs 13. The parts may be adjusted so that this difference will make a considerable movement of the pointer over the dial.

As soon as the heater is fully immersed, further descent will add to the pull on the sheave by an amount which will be represented by the difference in the specific gravities of cable and oil. This will change the backward movement of the pointer to a forward one. When the heater strikes the bottom of the well, its entire weight is removed from the pull on sheave 14, and the pointer suddenly moves backward again.

It will be evident that by watching the pointer and dial, a person can tell when the lowered heater reaches the surface of the oil, when it becomes fully immersed, and when it strikes the bottom. If the lower-

ing mechanism is provided with means for determining at any time what length of cable has been paid out, then these observations of the movements of the pointer will 5 serve as means for measuring the depth of the oil in the well. Or the depth may be determined by measuring the amount of cable paid out between the first and second backward movements of the pointer when the 10 heater is passing from a point above the oil to contact with the bottom of the well. Ordinarily, a rough estimate of the depth of the oil will be all that is necessary.

In practice, the heater is lowered to contact with the bottom of the well and then is 15 raised two or three feet, more or less, so that the entire weight is clear of any solid support. The nut 26 is then released and the pointer adjusted to a position between the 20 fingers on contact piece 30, as shown in Fig. 3. By again tightening nut 26, the pointer is secured in this position. The current is then turned on the heater, and permitted to stand that way until it is considered that 25 the well has been sufficiently heated.

As long as the heater remains submerged, and nothing special occurs, there will be no movement of the pointer. But if the oil in the well should subside and expose the end 30 34 of the heater, then there will be an increased pull on the cable of six pounds for each foot of heater exposed, and such increased pull will cause the pointer to move forward. If the parts are so adjusted to 35 each other that the pointer will move far enough to engage a finger of contact piece 30 before the entire length of the extension 34 is exposed, then the bell 32 will sound an alarm before the heater proper is exposed 40 above the surface of the oil.

A long cable with a heavy weight on its end will stretch an appreciable amount in its total length, tho the amount of such stretch is inappreciable in a short length. If the 45 walls of the well should cave in and cover the lower end of the heater, they would normally cover only a part of the extension 35. As there are no heating coils in this extension, no damage will occur as the result of 50 such caving of the walls. The part 35 is normally a spacing piece to avoid damage from ordinary caving of the walls.

Under the heating process, the caving in 55 of the walls below the casing is a process occurring at intervals. The circulation of the oil being heated, and the melting of the paraffin in the pores of the sand or rock, will cause a small caving in which will fill the space under the heater, and perhaps bury a 60 small portion of the extension 35. As the heat increases there is likely to be another caving in which will cover more of extension 35, and after several such cavings the falling material may cover part of the heater proper.

65 If something is not done to overcome this

difficulty, such covering will cause overheating and damage or destruction of the heater.

But during such process, the cable is stretching gradually under its load, and it is also lengthening by reason of being heated. 70 That part of the cable which is submerged is of the same temperature as the oil, which temperature is continually increasing as the heating process goes forward. Above the surface of the oil, the cable becomes gradually warmer and warmer by reason of the heat in the oil radiating to the air in the well over the oil, and also by the upward movement of the vaporized portions of the more volatile parts of the oil in the well. The combined stretch and expansion of the cable under pull and increasing heat cause the heater to move continually downward in the well. But if there has been a cave in of the walls so as to cover even a part of the extension 35, 85 then the downward movement of the heater will cause it to rest on the material which has fallen down under it. This will reduce the pull on the cable which in turn will cause a backward movement of the pointer and a consequent signal by the bell 32.

From the foregoing it will be seen that if a heater used in heating an oil well be subjected to conditions which will cause destructive overheating at either end of the heater, 90 notice of such condition will be given to the operator at or near the mouth of the well. Also, the indicator will give the operator information as to which end of the heater is in danger. If the upper end is exposed by reason of subsidence of the oil in the well, then the added pull on the sheave 14 will cause the bell to be sounded by a forward movement of the pointer. If the lower end be endangered by reason of caving in of the walls of the 100 well, then the decreased pull on sheave 14 will cause the bell to be sounded by a backward movement of the pointer. And further, the signal will give the operator information of either kind of accident before that accident 110 has progressed far enough to endanger the heater, or to cause as much damage as would amount to the burning out of a fuse. Caving in of the walls of the well is the most common accident endangering the heater. With this 115 apparatus, the difficulty is overcome by simply raising the heater a few feet so that it will be clear of the material which has fallen in.

What I claim is:

1. The combination with a device suspended by a cable in the oil of an oil well and used to heat the same, of an indicating device for indicating the occurrence of an accident liable to result in injury to the heating device, and means for using the expanding length of the cable to operate the indicating device so as to give information of the occurrence of the accident. 125

2. The combination with a device for heat- 130

ing the oil in an oil well, and a cable by which the heater is supported within the well, of means operating by decreased tension on the cable to indicate a caving-in of the walls of the well which would bury the lower end of the heater by the material falling from the walls.

3. The combination with a body to be inserted in the oil of an oil well, and a cable by which said body is lowered into the well, of means operating thru changed tension on said cable for indicating the degree of submergence of said body in the oil of the well.

CASPER L. REDFIELD.
